CLAIM

The ornamental design for a training platform, as shown and described.

DESCRIPTION

FIG. 1 is a front perspective view of a training platform showing my new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a perspective exploded view thereof as the claim is directed to the collective appearance of the objects shown. The broken lines depict unclaimed portions and environment of the training platform and form no part of the claimed design. The claim is directed to the collective appearance of the training platform as shown in the figures. The relative positioning of the parts forms part of the claimed design.
